UNITED STATES PATENT OFFICE

157,501

AIR CIRCULATOR UNIT

Jacob Walter Kisling, St. Louis, Mo.

Application February 27, 1948, Serial No. 144,781

Term of patent 7 years

(Cl. D26—7)

To all whom it may concern:

Be it known that I, Jacob Walter Kisling, a citizen of the United States, residing at St. Louis in the county of St. Louis and State of Missouri, have invented a new, original, and ornamental Design for an Air Circulator Unit, of which the following is a specification, reference being had to the accompanying drawing, forming a part thereof.

In the drawing:

Fig. 1 is a top plan view of an air circulator unit showing my new design;

Fig. 2 is a side elevational view of a unit in accordance with my new design, and

Fig. 3 is a side elevational view of the device

shown in Figs. 1 and 2, with parts broken away and shown in section.

I claim:

The ornamental design for an air circulator unit, substantially as shown.

JACOB WALTER KISLING.
